B. F. WREN,
HAME AND TRACE CONNECTOR.
APPLICATION FILED MAR. 27, 1908.

906,353.

Patented Dec. 8, 1908.

UNITED STATES PATENT OFFICE.

BENJAMIN F. WREN, OF BOERNE, TEXAS.

HAME AND TRACE CONNECTOR.

No. 906,353.

Specification of Letters Patent.

Patented Dec. 8, 1908.

Application filed March 27, 1908. Serial No. 423,713.

To all whom it may concern:

Be it known that I, BENJAMIN F. WREN, a citizen of the United States, residing at Boerne, in the county of Kendall and State of Texas, have invented new and useful Improvements in Hame and Trace Connectors, of which the following is a specification.

This invention relates to hames and connectors for coupling the traces therewith, the 10 main object of the invention being to provide a simple and effective construction of coupling means for attaching the trace to the hame at different elevations to suit different-sized horses, as well as to provide a connector 15 which will securely engage the hame against any possible liability of accidental disengagement and yet may be readily applied and removed at all times.

A further object of the invention is to provide a connector which will also securely hold the trace in position, and which is provided with locking devices of improved construction to respectively hold it in connection with the hame and trace.

With these and other objects in view, the invention consists of the features of construction, combination and arrangement of parts hereinafter fully described, and claimed, reference being had to the accompanying drawing, in which:—

Figure 1 is a perspective view illustrating the use of the invention. Fig. 2 is a top plan view of the connector. Fig. 3 is an outer side elevation thereof. Fig. 4 is a horizontal longitudinal section taken on line 4—4 of Fig. 3. Fig. 5 is a cross-section on line 5—5 of Fig. 3. Fig. 6 is a cross-section on line 6—6 of Fig. 3.

Referring to the drawing, the numeral 1 designates one of the hames of a harness, which is provided with a plurality of keepers 2, of loop form to receive the adjacent end of the connector hereinafter described, which hame and keepers may be constructed and combined in any preferred manner.

The hame and trace connector 3, which is designed for coupling a chain or other trace 4 with either one of the keepers 2, comprises an elongated bar having keeper and trace engaging ends. The keeper engaging end is provided with a forwardly projecting portion 5 constituting a hook and which is arranged in spaced relation to a guide lug or projection 6 formed with a longitudinal bore 55 or passage 7. Arranged for movement in the space between said hook and lug is a

latch 8 provided with a rearwardly projecting stem 9 slidably engaging the bore or passage 7, and formed with an inwardly extending bearing portion 10 and an outwardly extending finger piece or portion 11. The stem 7 and bearing portion 10, which latter bears against the adjacent portion of the face of the bar, guide the latch for movement in a straight path, and arranged between the lug 65 and rear portion of the body of the latch is a coiled spring 12 normally tending to hold the latch closed. To further guide as well as to strengthen the latch against the strains falling upon it, the portions 10 and 11 of the 70 latch are formed with a threaded bore to receive a right angular guide stem 13 movable in a slot 14 in the bar and provided at its inner end with a head 15 fitted to slide in a recess 16 in the bar communicating with said 75 slot, said recess being of greater length and depth than the slot so as to provide an intervening shoulder against which the head bears, whereby the latch is limited in its outward movement and strengthened against 80 the pressures and strains falling thereon. The portion of the bar adjacent the hook 5 is adapted to fit the side of the hame 1 and body portion of the engaged keeper 2, with hook 5 extending forwardly beyond said 85 keeper, which latter is received into a space 17 between the front face of the bar, the rear face of the forward portion of the latch, the bearing portion 10 and the inner surface of the hook 5, which face is formed by cutting 90 away a portion of the latch, thus providing for the secure retention of the keeper in position. The forward end of the latch is formed with a tongue 18 to engage a recess 19 in the hook, to more firmly and positively connect 95 said parts when the latch is projected.

The mode of engaging the hooked end of the connector with either keeper to connect the trace with the hame at a higher or lower point or elevation according to the size of the 100 horse will be readily understood, and it will be seen that by merely engaging the thumb or finger with the curved forward surface of the finger piece 11 of the latch the latter may be quickly slid backward to free the keeper and permit ready disengagement of the connector therefrom. Hence, the device may be readily connected with and disconnected from the hame even when the fingers of the hand are numb from exposure in cold 105 weather.

The rear end of the connector bar extends

in the form of a reduced shank 20, the rear or trace engaging end of which is provided with a downwardly and forwardly projecting hook 21 to engage the end link of the chain 5 trace 4 or an equivalent engaging member upon a trace of any other character. A latch 22 is provided to permit of the free engagement of the trace link with the hook 21 and to retain such link in connection therewith. 10 This latch is vertically disposed and is in the form of a substantially H-shaped plate bifurcated at its lower end to provide arms 23 straddling the forward end of the tongue 21 and pivotally connected therewith 15 by a transverse pivot pin 24, the upper wall of such lower bifurcation being upwardly and rearwardly beveled, as at 25, to permit said latch to be swung rearwardly and downwardly to retracted position, as shown in 20 dotted lines in Fig. 3, for the ready release of the trace link, the latch being supported against further downward movement in such position by the engagement of such beveled surface with the upper face of the hook 21. 25 The upper end of the latch is bifurcated to a less degree to provide short parallel arms 26 to engage the opposite sides of a guiding and bracing rib or web 27 formed upon the under-side of the shank by recessing the opposite 30 faces thereof, which recesses receive the said arms 26. By this means it will be apparent that the upper or free end of the latch will be effectively guided and braced securely against lateral or transverse strain. The latch lies 35 when in closed position at a forward inclination with its arms 26 resting against shoulders 28 formed at the forward ends of said recesses in advance of the pivot member 24, by which the latch is retained by gravity in 40 trace-retaining position and also by the trace link which limits its rearward movement and serves to support the latch in the event of the latter dropping backward out of closed position. The space between the hook 21 45 and lower surface of the shank is sufficient to permit of the link being slightly elevated so as to clear the latch and permit the latter to be fully turned down to an open position, so

that the link may then be readily moved out of engagement with the hook. 50

The mode of application of the device for connecting the trace with the hame is clearly shown in Fig. 1, and from the foregoing description of the construction it will be apparent that the invention provides a convenient and simple type of connector which may be easily and quickly connected with and disconnected from the hame and trace and will securely couple the parts together, and that the construction is also such as to adapt 60 the device to be manufactured and sold at a comparatively low cost. 65

Having thus fully described the invention, what is claimed as new is:—

1. A hame and trace connector comprising 65 a bar provided at its rear end with a trace-engaging portion and at its forward end with a guide lug and a keeper-engaging hook spaced therefrom, a latch movable in the space thus formed and having a stem slidably 70 engaging the guide lug and a second stem slidably engaging the bar, said second stem being formed to provide with the bar and hook a keeper receiving space, and a spring associated with the first-named stem and 75 disposed between the lug and latch to project the latter to closed position.

2. A hame and trace connector comprising 80 a bar provided at its forward end with hame engaging means, and having at its rear end a downwardly and forwardly projecting trace engaging hook and a central downwardly projecting guide rib arranged above said hook and forming receiving spaces at opposite sides thereof, and a retaining latch bifurcated at its lower end to straddle the hook and pivotally connected therewith and bifurcated at its opposite end to receive and 85 engage said rib and provide arms moving in said spaces. 90

In testimony whereof I affix my signature in presence of two witnesses.

BENJAMIN F. WREN.
